UNITED STATES PATENT OFFICE

EUGENE L. MESSLER AND JAMES M. GUTHRIE, OF PITTSBURGH, PENNSYLVANIA; SAID GUTHRIE ASSIGNOR TO JAMES THOMAS, OF SHARPSVILLE, PENNSYLVANIA

HOT TOP

Application filed October 31, 1928. Serial No. 316,309.

This invention relates to an improvement in a hot top for ingot molds.

It has been found in practice that solid metal hot tops are not satisfactory, chiefly because they chill the teemed metal and allow it to cool too quickly. This has driven the trade to the adoption of hot tops composed of refractory material.

The objection of hot tops composed entirely of refractory material is due to the fact that they wear and deteriorate so rapidly that a hot top may only be used in the casting of one, or possibly two ingots. Ordinarily, a hot top has a refractory portion extending several inches into the ingot mold to serve as a protection for the region of jointure between the hot top and the ingot mold, and to cool the hot metal and prevent its escape at this region. It is this depending portion of the hot top that often breaks, due to the forces of the cooling and contracting ingot.

The object of this invention is to provide a hot top structure having a metal reinforced outer casing, which is relatively substantial to permit its repeated use, and to provide an internal lining member for the casing to protect the region of jointure between the hot top and ingot mold.

In the accompanying drawings Figure I is a vertical sectional view through a hot top, showing a thin metal lining fixed therein; Figure II is a similar view through a slightly modified hot top structure; Figure III is a like view showing a further modified hot top structure; and Figure IV is a similar sectional view showing a still further modification of the invention.

Figure I of the drawings shows in vertical section a hot top designated by the reference numeral 1, and seated on the ingot mold 2. This hot top is cast of suitable metal, such as iron, and has an outer continuous wall 1^a. Adjoining the upper and lower extremities of the wall 1^a are the webs 1^b and 1^c respectively, and extending between the inner edges of said webs are a plurality of spoke or rib members 1^d. Arranged within the spokes 1^d is the relatively thin metal lining member 3. It will be noticed that the lining member may

be suitably fixed by outturning its upper edge 3^a over the web 1^b.

The lining 3 is extended several inches into the ingot mold 2. The reason for this is to prevent metal, during the teeming operation, from flowing out the line of jointure 4 between the hot top and the ingot mold. It has been found that this structure causes the metal to congeal or solidify in the region 5, before it reaches the said line of jointure.

It is the function of the spokes or ribs 1^d to support the lining member throughout its length in the hot top, and prevent the same from bulging or distorting, due to the weight and heat of the metal teemed into the ingot and hot top. Between the lining member and the wall 1^a of the hot top there is a space 6 of considerable volume. Into this space there may be suitably fixed a refractory material, such as fireclay or refractory brick. However, the hot top is illustrated without the interposition of a refractory substance, as just mentioned; since it was found that the constrained air in this space served as an insulating medium.

By forming the wall 1^a and the spokes 1^d of relatively slight thickness, the loss of heat by conduction is minimized. A cap 7, as shown in dotted lines, may be desirably employed to cover the pouring hole 8 after the ingot has been teemed.

Figure II shows a slightly modified form of hot top, and comprises an outer casing of metal 9 having the refractory material 10 retained therein. The flanges 9^a and 9^b are provided to secure and position said refractory material within the hot top. It should be noted that the refractory material 10 may be packed into the casing 9 and hardened therein by a burning or baking operation, similar to that used in burning firebrick. The lining member 3 is similarly mounted in this form of hot top to serve purposes identical with those described in connection with Figure I.

Figure III shows a still further modified form of hot top 13. This latter hot top comprises an outer casing 13^a having fibrous asbestos or infusorial earth 14 packed therein, and an inner wall member 15 affixed to the

webs 13^b and 13^c of the hot top, as illustrated. A lining member 3 is represented in broken lines; the upper edge 3^a thereof, however, is shown before it is out-turned to engage the hot top.

Figure IV shows a still further modified form of this invention, and comprises a hot top 16. In this form of hot top, a core 17 is baked according to usual foundry practice, and the metal walls 16^a and 16^b, and the flanges 16^c and 16^d are all formed in one casting operation around the said core, which is allowed to remain within the hot top to serve as heat insulating material. A lining member 3 may be affixed in this hot top in the same general manner as that described supra, in conjunction with the other forms of hot tops.

It is preferable to allow the lining members 3 to remain on the sinkhead of the ingot, and be sheared off the same therewith. To afford means of attaching stripping tackle to the hot tops, there is provided the eye lugs 18, which are cast integrally with the outer shells of the hot tops.

The structures herein disclosed provide a hot top which may be used in the teeming of an indefinite number of ingots, the inexpensive lining member being the only element thereof that requires replacement for the pouring of each ingot.

What we claim is:

1. A hot-top for ingot molds comprising a metallic shell including insulating material, together with a thin lining member inwardly covering said metallic shell from direct contact with molten metal.
2. A hot-top for ingot molds comprising a metallic shell having an outer wall with insulating material positioned adjacent thereto and inner shell portions retaining the insulating material so positioned, together with a thin metallic lining member inwardly covering the inner metal shell portions from direct contact with molten metal.

In witness whereof, we hereunto set our hands.

EUGENE L. MESSLER.
JAMES M. GUTHRIE.
